US00D725526S

(12) **United States Design Patent**
Graff

(10) **Patent No.:** **US D725,526 S**
(45) **Date of Patent:** **** Mar. 31, 2015**

(54) **WATCH DIAL**

(71) Applicant: **Laurence Graff**, Gstaad (CH)

(72) Inventor: **Laurence Graff**, Gstaad (CH)

(73) Assignee: **Graff Diamonds SA** (CH)

(**) Term: **14 Years**

(21) Appl. No.: **29/508,167**

(22) Filed: **Nov. 4, 2014**

(51) **LOC (10) Cl.** **10-07**

(52) **U.S. Cl.**

USPC **D10/126**

(58) **Field of Classification Search**

CPC G04B 19/06; G04B 19/10

USPC D10/123-126, 30-39, 6, 22-29;
368/223, 228, 232
